SPRAY NOZZLE

Oscar Manning, Los Angeles, Calif.

Application October 21, 1952, Serial No. 21,921

Term of patent 14 years

(Cl. D91—3)

To all whom it may concern:

Be it known that I, Oscar Manning, a citizen of the United States, residing in the city of Los Angeles, in the county of Los Angeles and the State of California, have invented a new, original, and ornamental Design for a Spray Nozzle, of which the following is a specification, reference being had to the accompanying drawings, forming part thereof.

Fig. 1 is a side elevational view of a spray nozzle in closed position showing my new design;

Fig. 2 is a similar view thereof in open position;

Fig. 3 is a top plan view thereof in closed position;

Fig. 4 is a similar view in open position;

Fig. 5 is a bottom plan view thereof;

Fig. 6 is a similar view in open position;

Fig. 7 is a front view thereof taken from the left of Fig. 1; and

Fig. 8 is a rear view thereof taken from the right of Fig. 1.

I claim:

The ornamental design for a spray nozzle, substantially as shown.

OSCAR MANNING.
